CONTINUOUS COKING STILL

Joseph B. Weaver, New York, N. Y.

Application April 29, 1931. Serial No. 533,586

7 Claims. (Cl. 202—106)

This invention relates to an improved coking still primarily adapted for use in handling heavy petroleum residues of, for example, the residual oils discharged from oil cracking systems, and wherein the construction of the still is such as to provide for the positive advance of such residues through the heating elements or retorts of the still while the residues are being subjected to sufficient heat to effect the removal as vapors of the volatile constituents thereof, the vapors being removed from the upper portions of said retorts contiguous to the point of introduction of the residual oils into said retorts, while the volatile-freed coke is continuously removed from the lower portions of said retorts.

In the operation of coking stills, considerable difficulty has been encountered in the matter of preventing the thick viscous coke from adhering to the walls of a retort and choking or clogging the retort against the proper movement of the petroleum residues therethrough. The coke has a tendency when subjected to the proper degree of heat necessary to deprive the same of its volatile matter, to harden and build up tenaciously clinging deposits or incrustations on the heating retort walls and these deposits interfere with proper heat transfer between the heating medium, such as furnace gases, and the petroleum residues undergoing such heat treatment in the retort. To provide for continuous or sustained operation for extended periods of time of such a retort, it is, therefore, important that provision be made for insuring the desired progressive advance of the petroleum residues through the heating chamber or retort, whereby as the residual oils are continuously introduced into one portion of the retort, the substantially solid petroleum coke may be likewise continuously removed from another portion of the retort and wherein, at the same time, provision be made for constantly scraping or otherwise mechanically removing the heated mass of petroleum in the retort from not only the walls of the retort but also from the walls of the agitating or scraping means, whereby the full length of the retort or coking chamber may be kept in an open condition permitting of the desired passage of the volatiles in a direction countercurrent to the passage of the residues or coke through the retort and the retort also kept open to provide for the sustained advance of the pitchy tarry mass from which the coke is formed.

In attaining these ends, I have provided a coking still which is formed to comprise a furnace having arranged in the path of furnace gas travel a longitudinally extending retort disposed

at an acute angle with respect to the vertical and wherein each retort, since there may be a plurality of them disposed within the furnace, is formed to comprise a pair of adjoined tubes which are in open communication along their adjacent sides, each of the tubes being equipped with a longitudinally extending rotor mounted to revolve about the longitudinal axis of each tube, the said rotors being provided with interengaging blades and a drive mechanism is provided, which is arranged exteriorly of the furnace, for imparting intermittently and alternately rotary motion to said rotors, whereby movement is imparted to one of said rotors to cause the latter to engage and scrape coke from the side walls of its chamber or tube and the adjacent surfaces of the adjoining complementary rotor. The drive mechanism is such that following this operation, the first rotor is brought to a stand still and the second complementary rotor operated so that it may be moved to scrape coke from the walls of its tube and the adjoining surfaces of the first of said rotors.

The construction and operation of the rotors is therefore such as to provide for their self-cleaning as well as the cleaning of the longitudinally extending apertures formed between the blades of the rotors and the inner walls of the rotor.

The coking still further provides for a gas sealed outlet through which the coke formed in the rotor is discharged; the provision of a nozzle structure for introducing petroleum residues into the upper portion of the retort and wherein the nozzle is equipped with means by which its aperture may be cleaned of coke deposits; the provision of means for utilizing economically the heat of the furnace and the heat of the products discharged from the retort for the development of steam and in other ancillary capacities and, also, the provision of a coke still of simple mechanical construction and of efficient operation.

With these and other objects in view, which will appear as the description proceeds, the invention consists in the novel features of construction, combination of elements and arrangements of parts hereinafter fully described and pointed out in the appended claims. In the accompanying drawings:

Fig. 1 is a vertical sectional view taken through a continuous coking still constructed in accordance with the present invention;

Fig. 2 is a horizontal sectional view taken through the vapor outlet of the still on the plane indicated by the line 2—2 of Fig. 1;

Fig. 3 is a horizontal sectional view taken through one of the double tube retorts of the still and disclosing the formation of the scraping rotors mounted therein, the plane of the section being disclosed by the line 3—3 of Fig. 1;

Fig. 4 is a vertical sectional view disclosing the drive mechanism for the rotors, as indicated by the line 4—4 of Fig. 1;

Fig. 5 is a horizontal sectional view on the plane indicated by the line 5—5 of Fig. 4;

Fig. 6 is a similar view on the line 6—6 of Fig. 4 and disclosing more particularly the interrupted gears for effecting the rotation of the scraping rotors;

Fig. 7 is a vertical sectional view taken through the coke outlet of the retort on the line 7—7 of Fig. 1;

Fig. 8 is a vertical sectional view on the line 8—8 of Fig. 7;

Fig. 9 is a detail vertical sectional view on the line 9—9 of Fig. 1;

Fig. 10 is a diagrammatic view disclosing the operation of the coking still and associated condensing and heat exchange apparatus;

Fig. 11 is a similar view showing a slightly modified form of the invention.

Referring more particularly to the drawings, the numeral 1 designates the coking still comprising the present invention in its entirety.

This still is formed to embody a furnace formed from suitable heat retaining walls, including in this instance a vertical front wall 2, an inclined rear wall 3, top and bottom walls 4 and 5 respectively, disposed substantially perpendicularly to the plane of the rear wall 3, and vertical side walls 6. Also arranged in the furnace is an inclined bridge wall 7 which extends substantially parallel to and spaced from the rear wall 3. Between the bridge wall 7 and the front wall 2,

the furnace includes a combustion chamber 8 and desired furnace temperatures may be obtained within this chamber by the provision of combustion producing burners or other equivalent apertures 9. The gases of combustion pass upwardly through the chamber 8 and thence downwardly through a retort chamber 10 formed between the bridge wall 7 and the rear wall 3 and after traversing the chamber 10, the gases are delivered to a vertical outlet stack or flue 11.

It will be understood that the walls of the furnace may be of any desired construction customary in the building of furnaces of this character and therefore a further explanation relative to the design or structural characteristics will be omitted. The burner 9 may be of the oil or gas type or mechanism may be substituted therefor adapted for the burning of solid fuels and it will be appreciated that these are details which may be varied depending upon the particular conditions of economy which prevail when the stills are to be operated.

Extending longitudinally through the retort chamber 10 between the bridge wall 7 and the rear wall 3 and also through the space establishing communication between the upper portions of the chambers 8 and 10 is a retort 12. While but one retort has been illustrated in the accompanying drawings, it is to be understood that the furnace may contain as many of these retorts as may be needed to secure a certain desired working capacity on the part of the still. However, since such additional retorts will constitute but a mere duplication of the one depicted, a detailed description of such retort will suffice for all.

In its preferred form, the retort 12 comprises

a plurality of longitudinally aligned double tube sections 13 which are secured together by fastening devices passing through the flanged meeting ends 14 thereof. The double tube sections are each of integral formation and the said sections are in open communication along their adjoining sides, as disclosed in Figs. 2, 3 and 5. The upper section of the retort is loosely received in the top wall 4, whereas the lower of said sections passes through the bottom wall 5 and is directly secured to a rigid bed casting 15 which is mounted upon the furnace foundation 16. This construction permits the retort to expand and contract in response to fluctuating temperature conditions, without detrimentally effecting the efficiency of the furnace structure. Preferably, the retort 12 is arranged at an angle of approximately 30° with respect to the vertical. This angle is such as to provide for maximum length of the retort within the furnace and to control more effectively the desired gravitational feed of the coking material through the retort in order that it may be subjected to the temperatures of the furnace for the necessary period of time. Also the angle of the retort serves to minimize clogging or choking of the passages of the retort with the coke or coke forming materials during the operation of the retort.

Steam jacketed residual oil inlets 17 are provided in connection with the upper end of the retort 12, there being an inlet for each of the tubes of the retort. Heavy petroleum residues, such as the residual oils of cracking systems, as will be hereinafter specified, pass into the inlets 17 by way of suitable valve controlled pipes 18 and thence downwardly through restricted passages 19 wherein the oils enter the upper portion of the retort. The passages 19 may be cleaned of coke or other obstructing matter by means of screw threaded plungers 20 which are movable into and through the passages 19 to scrape accumulated matter from the walls thereof, thus keeping the passages 19 free and allowing for unrestricted oil flow into the retort 12. By steam jacketing the passages 19, coke formation therein is minimized as the oil passing through the passages is maintained at a temperature sufficiently low to prevent any appreciable coking thereof.

The residual oils, after being introduced into the upper portion of the retort 12, pass slowly downwardly through said retort and are subjected to the internal temperatures of the furnace, the temperatures imparted to the residual oils being sufficiently high to deprive said oils of their lower boiling or volatile constituents, causing the vaporization of said constituents and their upward travel through the retort, where they are taken off at the upper end of the retort through an outlet 21. As the oils or residues pass downwardly through the retort and the temperatures thereof increased and the vaporizable compounds removed, such residues become increasingly heavy, thick and viscous, possessing a tarry consistency which renders the same extremely difficult to handle even in large size tubes. This slow moving tarry mass tends upon contact with the heated walls of the retort to coke and produce a hardened deposit which, if not removed, would soon obstruct and arrest the operation of the still. Therefore, it is important that means be provided for positively effecting the progressive travel of the coke or tar through the retort and to prevent the same from accumulating on the walls of the retort. The best means I have found for attaining this result consists in the provision of a pair

of tri-bladed cast iron rotors 22-22. These rotors are positioned longitudinally in the double tube sections of the retort and are suitably keyed on steel shafts 23, passing longitudinally and axially through the tubes of the retort. The lower ends of these shafts are received within stuffed bearings 24, provided in the bottom of the retort, and the lower ends of the shafts 23 project beyond the bearings 24 and are mounted for rotation on efficient types of thrust bearings 25, carried by the bed casting 15. The upper ends of the shafts 23, above the rotors 22, are received within bearing webs 26 formed in the upper portion of the retort 12 contiguous to the vapor outlet 21.

The outer portions of the rotors 22 move in orbits which approximately equal the inner diameter of each of the retort tubes 13, and the orbits of the tube retorts overlap. To permit of intermittent and alternate rotary movement of said rotors, the side walls of the blades of said rotors are curved as at 27 on arcs corresponding to the inner diameter of the retort sections or the orbits of rotation of said rotors. By this construction, the rotors scrape or remove carbon or coke deposit from the walls of the retorts and at the same time scrape or remove such coke or carbon from the walls of the rotors themselves, whereby the material passing through the retort is prevented from accumulating on any part of the interior of the retort and is kept in a constant state of agitation or motion causing the positive travel of the petroleum residue through the longitudinally extending apertures formed between the several blades of the rotors.

The mechanism for imparting motion to the rotors has been particularly disclosed in Figs. 4 and 6, but it should be understood at this juncture that I do not limit myself to any specific means for effecting the operation of the rotors, the mechanism illustrated being merely one of several advantageous drives. As shown in Fig. 4, the bed casting 15 is provided with a horizontally extending shaft 28 journaled with its ends in bearings 29. This shaft has fixed thereto spaced and opposed mitre gears 30, which constantly mesh with similar gears 31 provided upon the lower ends of vertically journaled countershafts 32, which are supported for rotation in bearings 33, formed with the bed casting. As shown in Fig. 4, the counter shafts 32 are provided with interrupted gears 34 which mesh with the teeth of somewhat similar gears 35 which are keyed to the lower ends of the rotor shafts 23. The counter shafts 32 are constantly driven from the shaft 28, causing continuous rotation of the gears 34 in the directions indicated by the arrows in Fig. 6. With the rotors in the positions disclosed in Fig. 5, it will be seen, by reference to Fig. 6, that the rotor on the right of the figure is in a state of rotation while the rotor on the left is stationary. The stationary rotor is locked against movement by the fact that the gears 34 are provided with plain, toothless perimeter portions which engage with an enlarged arcuate tooth 37 formed on each of the gears 35 of the rotor shafts. By reference to Fig. 6, it will be noted that when the tooth 37 of the gear 35 is in engagement with the plain perimeter portion 38 of the gear 34, the gear possessing the tooth 37 in such engagement will be locked against rotation and, likewise, the rotor driven by the stationary held gear 35 will be correspondingly retained against rotation. The moving rotor revolves through substantially one-third of a com-

plete circle when, due to the construction of the interrupted gearing, the rotor comes to a rest and is locked against further movement. At this point, the other rotor is revolved and the operation continues producing an intermittent or alternate movement or state of rotation on the part of said rotors. I do not claim broadly the construction of the rotors or the intermittent drive mechanism therefor, as this mechanism has been disclosed in the patent to Maxwell McGuinness, No. 1,793,026, dated March 24, 1931, but I do claim as my invention, as will be hereinafter more fully defined in the appended claims, the use of such rotors in a continuous coking still of the character herein set forth.

The coke formed in the operation of the rotor is discharged from the bottom of the retort through an outlet 39 formed in connection with the bed casting 15. To seal this outlet against the passage of vapors or gases, I provide therein, as disclosed in Figs. 7 and 8, rotors 40 which are of the same construction and operation as the rotors 22. The rotors 40 are driven by the gearing 41 which, in turn, is operated by a chain and sprocket drive 42 extending from the drive shaft 28. The gearing 41 has been conventionally illustrated but it will be understood that it may be of the same character as the gearing illustrated in Fig. 6. The rotors 40 serve to provide for the free passage of the coke through the outlet 39 and yet seal this outlet against the passage of vapors and gases, permitting the desired internal pressures within the retort to be maintained and to insure delivery of vapors and gases through the vapor outlet 21 provided in the upper portion of the retort. The coke discharged from the rotors 40 drops upon a screw conveyor 43 and is transferred to a suitable point of discharge.

In view of the foregoing, it will be seen that the present invention provides a coking still wherein a self-cleaning conveyor is utilized. The operation of the conveyor permits of the scraping of all surfaces thereof at every revolution and serves to positively translate the substances which are being treated from rotor to rotor. The still thus comprises one or more double retort tubes set at an angle of approximately 30° from the vertical, and each double tube is fitted with the two rotors 22. These rotors are driven, as explained, from the lower end of the tube, at which point the tube is originally fastened to the bed casting 15, expansion and contraction being provided for by allowing the upper end of the tube or retort to be free in the furnace setting, as well as the rotors themselves being free to expand inside the tubes. The residues to be reduced are admitted at the top of the rotor sufficiently far from the upper end to eliminate the entrainment of liquids which have not been treated in outgoing vapors. These residues are progressively advanced through the retort and are heated during this travel sufficiently to drive off all the volatiles, leaving a substantially dry coke which crops out of the lower end of the retort upon the screw conveyor 43.

The operation of the entire system of which the coking still forms a part is best explained by reference to Fig. 10. Petroleum residues are introduced into the upper end of the retort by the passage 19 and first pass through a heat exchanger 44. The residues entering the heat exchanger may possess a temperature of approximately 200° F. to 250° F. and after being heated by vapors discharged from the upper end of the retort, the said residues attain a temperature of 150

approximately 660° F., at substantially which temperature they are introduced into the upper end of the coking retort. The volatiles discharged from the vapor outlet 21 possess an approximate temperature of 800° F. and, commingled with superheated steam, pass through the heat exchanger 44 so that their temperatures may be reduced to approximately 350° F. From the heat exchanger 44, the vapors then pass into a steam generator 45 which contains a steam generating coil 46, and in this steam generator, due to the transfer of heat, the temperature of the volatiles is further reduced to approximately 250° F. From the generator 45, the volatiles then pass into a condenser 47 and finally to a separator 48, where the oil is separated from the condensed steam and both water and oil independently drawn off through the lines 49 and 50 respectively.

The residues, during the process of evaporation in the retort pass generally downwardly, the coke falling into the conveyor 43, at which point, in order to utilize efficiently the heat contained in the coke, since the latter possesses a temperature of approximately 850° F., water will be introduced by way of the line 51 to generate steam and to cool the coke down to a temperature of approximately 300° F. Water is also introduced into the coil 46 in the steam generator 45 and passes from said coil by way of a line 52 into a superheater 53, disposed in the stack or waste gas flue 11 of the furnace. In this superheater, the temperature of the steam is raised to approximately 1000° F., and the superheated steam passes from the superheater into the lower end of the retort by way of the pipe line 54. In the modification of the invention disclosed in Fig. 11, water is directly introduced in fine jets into the vapor outlet 21. In this arrangement, the water is introduced in a very fine spray in sufficient quantities to condense only the oil vapors, allowing the steam to escape at sufficiently low pressures in order not to in any way disturb the pressure balances in the retort. This operation avoids the use of the heat exchange apparatus 44, 45 and 47 disclosed in Fig. 10.

The residue introduced into the coking still may be handled in its retort. These residues are typical of reduced Seminole crude oil.

Gravity-----

12° A. P. I.

50 Volatiles-----

79% by volume

Weight, per U. S. gallon-----

8.2 lbs.

Specific heat-----

.90 at 800°

60 Gravity-----

33° A. P. I.

.79 gallons produced per gallon of residue charged.

With respect to the intermittent drive for the 65 rotors 22, it will be observed that one rotor of this device remains still while the other rotor makes one-third of a revolution, the second rotor coming to rest and remaining stationary while the first rotor makes one-third of a revolution. This 70 movement is preferably accomplished by the interrupted gear shown although other equipment and mechanisms may be utilized without departing from the invention. The dry coke gradually finds its way to the bottom of the retort where it 75 is passed out through the two small rotors 40,

which act as gas-tight valves, the coke being finally delivered to a screw conveyor 43. There are two injection nozzles 19 at the top of the rotor, each nozzle introducing the residues over the center line of each rotor. Each injection nozzle is provided with a plunger 20 which may be forced down through the nozzle to clear out any coke which may be formed at the entrance to the rotor. The nozzle is provided with a steam jacket, for the purpose of keeping the interior sufficiently cool to prevent excessive coke formation. 80 85

Attention is drawn to the design of the rotor which takes care of, in a simple way, the expansion and contraction which will occur. The double retort tubes are rigidly held at the bottom 90 and allowed to expand in a general vertical direction allowing for ample clearance to take care of the internal, as well as the external, expansion in a longitudinal direction; and, as a complete coking still requires a multiplicity of these retort 95 tubes, such tubes will be separated a sufficient distance apart so that they may expand and contract laterally inside of the furnace, being rigidly held at the lower end by suitable connections to the bed plate or foundation. 100

Any suitable pressure may be carried on the material passing through the retorts 12 or if desired, the retort may operate with sub-atmospheric pressures. Any suitable charging stock may be supplied to the retorts, including not only 105 high boiling petroleum oils, but crude oils, coal tar products, shale oils and other oleiferous materials. It is not necessary that the residues from the operation of the retorts should be carried down to coke or other form of solid residues. In 110 certain operations, it may be desirable to remove the residues as a heavy liquid or as semisolids.

What is claimed is:

1. A continuous coking still comprising a furnace, a retort disposed in said furnace at an acute 115 angle to the vertical, said retort being provided with a pair of parallel longitudinally extending chambers in open communication with each other along their adjoining sides, a pair of rotors mounted in said chambers to extend longitudinally thereof, said rotors being provided with inter-engaging blades having arcuate surfaces, the orbits of said rotors being disposed in overlapping relation, power driven means for intermittently and alternately imparting rotary movement to said rotors, means for introducing a heavy 125 petroleum oil into the upper portion of said retort, an outlet for discharging coke from the lower portion of said retort, and an outlet for the release of volatile constituents of said oil provided in the upper portions of said retort contiguous to the point of introduction of said residual oils. 130

2. A coking still comprising a furnace, a double tubed retort arranged in said furnace and disposed at an acute angle with respect to the vertical, multi-bladed rotors mounted for rotation in the tubes of said retort, said rotors having overlapping orbits, the side walls of the blades of said rotors being curved, the radii of which correspond to those of said tube, means for intermittently and alternately imparting partial rotary movement to said rotors and for momentarily locking a rotor during active movement of the complementary rotor, means for introducing a heavy petroleum coke forming oil into the upper 140 portion of said retort, a coke outlet provided in the lower portion of said retort, and a vapor outlet provided in the upper portion of said retort. 145

3. A continuous coking still comprising a furnace formed to include a setting, said setting be- 150

- ing formed internally to provide a combustion chamber and a retort chamber, a bridge wall separating said chambers, communication between said chambers being established over the 5 upper portion of said bridge wall, combustion developing means disposed in said combustion chamber and a waste gas outlet communicating with the lower portion of said retort chamber, a tubular retort mounted in said retort chamber 10 and extending longitudinally therethrough and through the upper and lower walls of the setting, a base member to which the lower portion of said retort is rigidly connected externally of said setting, said retort passing freely through the 15 walls of said setting to expand and contract freely with respect thereto, means for introducing a petroleum residue into the upper portion of said retort, self-cleaning agitating means arranged in said retort for effecting the positive advance 20 of said residue therethrough, a coke outlet communicating with the bottom of the retort, and a vapor outlet connected with the upper portion of said retort.
4. In a coking still, a furnace including heat 25 retaining walls and combustion producing means, a tubular retort disposed in said furnace and operatively arranged at an angle of substantially 30 degrees with respect to the vertical, the lower portion of said retort being arranged to project 30 through and below an opening in one of the lower of the walls of said furnace, rotatable cutters for removing coke from the inner surfaces of said retort and the surfaces of the cutters themselves, a base member mounted independently and ex- 35 traneously of the furnace walls and to which the lower end of said retort is secured, said base member serving to effect the support and sustain the weight of the retort substantially independently of the furnace walls, and motion trans- 40 mitting means carried by said base member for driving said cutters.
5. A coking still comprising a furnace formed to include heat confining walls and combustion producing means, a tubular retort arranged in 45 said furnace and disposed in acute angular relationship with respect to the vertical, the ends of said retort passing freely through openings formed in the upper and lower walls of said furnace, a base member arranged exteriorly of the 50 walls of said furnace and directly connected with the lower end of said retort to support substantially the weight of the latter when in its operative position within the furnace whereby to absorb the longitudinal thrust of the retort, rotors 55
- revolubly mounted in said retort, means carried by the base member for imparting movement to said rotors, an oil inlet communicating with the upper part of said retort, a vapor outlet in the upper part of said retort, and a coke outlet formed in connection with said base support and in communication with the lower end of said retort. 80
6. Heating apparatus for reducing heavy hydrocarbon oils to coke and vaporizable oils comprising a furnace formed to include heat confining walls and combustion developing means, a tubular retort projecting through the walls of said furnace in acute angular relationship with respect to the vertical, a base member connected with the lower end of said retort for supporting the latter in its operative position within said furnace independently of the walls of the latter, means for introducing oils to be heated into the upper region of said retort, means for removing vapors of said oils from the upper portion of said retort, a coke outlet communicating with the bottom of said retort, rotatable means disposed in said retort for removing coke from its inner surfaces and effecting the positive discharge of said coke through said outlet, and means for utilizing 95 the heat remaining in the furnace gases following the passage of the latter over said retort to directly heat the products within said retort prior to their discharge from the vapor and coke outlets. 100
7. Heating apparatus for reducing heavy hydrocarbon oils to coke and vaporizable oils comprising a furnace formed to include heat confining walls and combustion developing means, a tubular retort projecting through the walls of 110 said furnace in acute angular relationship with respect to the vertical, a base member connected with the lower end of said retort for supporting the latter in its operative position within said furnace independently of the walls of the latter, 115 means for introducing oils to be heated into the upper region of said retort, means for removing vapors of said oils from the upper portion of said retort, a coke outlet communicating with the bottom of said retort, rotatable means disposed 120 in said retort for removing coke from its inner surfaces and effecting the positive discharge of said coke through said outlet, and self cleaning valve rotors in the coke outlet of said retort serving to maintain the internal working pressures of the retort while effecting a substantial 125 constant discharge of coke through said outlet. 130

JOSEPH B. WEAVER.
